UNITED STATES PATENT OFFICE.

CHARLES H. SWANSON, OF CHICAGO, ILLINOIS, ASSIGNOR TO THE A & A MANUFACTURING COMPANY, OF CHICAGO, ILLINOIS, A CORPORATION OF ILLINOIS.

LIQUID-FUEL BURNER.

1,135,072.

Specification of Letters Patent. Patented Apr. 13, 1915.

Application filed July 26, 1913. Serial No. 781,301.

To all whom it may concern:

Be it known that I, CHARLES H. SWANSON, a citizen of the United States, residing at Chicago, in the county of Cook and State 5 of Illinois, have invented certain new and useful Improvements in Liquid-Fuel Burners, of which the following is a specification.

My invention relates to liquid fuel burners, and refers particularly, although not exclusively, to burners which are adapted to be used in connection with torches.

In the past it has been a matter of great difficulty to obtain a liquid fuel torch in 15 which the combustion is sufficiently perfect in order to make it possible to use a low grade liquid fuel, such as kerosene or the like. I have discovered that very perfect combustion may be obtained by providing 20 one or more preheating tubes, preferably U-shaped, which communicate on one end with the source of liquid fuel and through which the fuel passes and is gasified before it reaches the nozzle of the burner. On escaping from this nozzle the fuel is ignited 25 and the flame comes in proximity with the preheating tube or tubes so that the liquid fuel is gasified in such tubes. The preheating tube or tubes are attached at their ends 30 to a head, which is provided with a passage communicating with the interior of the tubes, this passage being controlled by means of a suitable valve. Inclosing the preheating tube or tubes is a flame retaining 35 shell which is apertured in order to admit the necessary air for purposes of perfect combustion. These and other advantages of my invention will be more readily understood by reference to the accompanying 40 drawings, in which—

Figure 1 is a vertical longitudinal section through the burner, in connection with which a portion of the tank with which the burner may be used is shown; Fig. 2 is a plan 45 of the burner, the flame retaining shell being shown in longitudinal section; and Fig. 3 is a fragmentary vertical section showing the method of connecting the burner tube to the tank tube.

The burner, which constitutes the subject-matter of my invention, consists of a head 50 having therein a passage 11 closed by the plug 12 and a passage 13 communicating with the passage 11. At the end of the passage 55 13 adjacent to the passage 11 is the

valve seat 14 adapted to be engaged by the needle valve 15 controlled by the handle 16 and having threaded engagement with the projection 17 which is preferably integral with the head 10. The head 10 also is provided with the nozzle lug 18 into which the nozzle 19 is screwed, this nozzle communicating with the passage 11 of the head 10.

At its upper end the head 10 is provided with the boss 20 through which the passage 60 13 extends, and to this boss is fastened one end of each of the U-shaped preheating tubes 21, 21. In the drawings I have illustrated two of these preheating tubes, but it will be understood that a single tube, or any 65 number, may be employed without departing from the spirit of my invention. The tubes 21 have their ends projecting slightly into the boss 20 in order to form a substantial connection therewith. If more than a 70 single preheating tube is used, the passage 13 is flared at its end in order to establish connection with all of these tubes.

At its lower end the head 11 has the boss 80 22 to which the opposite ends of the preheating tubes 21 are attached, these tubes preferably projecting slightly into the boss 22. The boss 22 is provided with the passage 23, which communicates with the preheating tubes 21 and the burner tube 24. 85 The burner tube 24 is attached by any suitable means to a tube 25 through which the supply of liquid fuel passes. In the embodiment of my invention illustrated herein I have shown the burner tube 24 as being removably attached to the tank tube 25 by means of the tapering sleeve 26, which is brought into engagement with the inner surface of the plug 27 attached to the tank 28 by means of the nut 29, which has threaded 90 engagement with the upper portion of the plug 27. The tank tube 25 passes to a point near the bottom of the tank 28. The tank 28 is supplied with the air pump 29, of any suitable construction. The top of the tank 95 has a depression forming the priming cup 30.

Attached to the bosses 20 and 22 of the head 10 is the retaining ring 31, which is adapted to receive the removable retaining shell 32, the inner surface of which engages the preheating tubes 21. The flame retaining shell 32 has the air inlet aperture 33 near its base, and is also preferably provided with the apertures 34, the purpose 100 105 110

of which will be explained hereafter. The flame retaining shell 32 also is provided with the end member 34 which serves to contract and direct the flame, as will be presently described.

As best shown in Fig. 2, the preheating tubes 21 engage each other through the portions of the tubes adjacent to the bosses 20 and 22, but are separated from each other 10 through the portions 35 of said tubes in order to allow the free passage of combustible gases and the flame resulting therefrom.

Having thus described the construction of my improved burner, its operation may now 15 be readily understood.

A readily combustible liquid, such as alcohol or the like, is placed in the priming cup 30, and on being ignited serves to heat the burner tube 24 and the lower portions of the 20 preheating tubes 21. After these tubes have been thoroughly heated and after air has been pumped into the tank 28 by means of the pump 29, (in order to force the liquid fuel within the tank 28 up through the tank 25 tube 25) the valve 15, which has been previously seated against its seat 14, is opened so that the fuel which has been gasified in the burner tube 24 and the lower portions 30 of the preheating tubes 21 is allowed to pass from the passage 13 into the passage 11. This gas next passes through the nozzle 19, and on account of its pressure air is drawn in through the apertures 33 of the flame retaining shell 32 and is mixed with said combustible gases. These gases then ignite toward the outlet end of the flame retaining shell 32, and serve to heat the preheating tubes 21. By means of the end member 34 35 the flames are concentrated and directed as desired. The apertures 34^a act as additional air inlets to aid in producing perfect combustion.

It will be evident from the above description that the preheating tubes 21 are constantly subjected to the heating action of the burning gases coming from the nozzle 19, and in this way the liquid fuel passing through said tubes is gasified long before it reaches the ends of the preheating tubes 50 which are attached to the boss 20.

I have found that by my improved construction very perfect combustion is pro-

duced so that a low grade fuel, such as kerosene, may readily be employed with excellent results.

It will be apparent to those skilled in the art that many changes could be made in the detailed construction of the parts which I have described without departing from the spirit or scope of my invention.

What I claim is:

1. In a liquid fuel burner, the combination of a preheating tube adapted for connection with a source of fuel, of a head having a passage therein communicating with said preheating tube and having a portion at substantially a right-angle thereto, said passage provided with a valve seat adjacent to said preheating tube, a valve adapted to engage said seat and to interrupt the flow of fuel through said passage, and a nozzle communicating with said passage in said portion of the latter at substantially a right-angle to said preheating tube, said nozzle adapted to direct the ignited fuel into proximity with said preheating tube, whereby the liquid fuel is gasified in its passage through said tube.

2. In a liquid fuel burner, the combination with a U-shaped preheating tube, of a head having an outlet passage therein communicating with one end of said preheating tube and an inlet passage communicating with the opposite end of said preheating tube, said outlet passage provided with a valve seat near one end thereof, a valve adapted to engage said seat and to interrupt the flow of fuel through said passage, and a nozzle communicating with said passage near the opposite end thereof and located substantially midway between the points of communication of said outlet passage with one end of said preheating tube and of said inlet passage with the opposite end of said preheating tube, said nozzle adapted to direct the ignited fuel into proximity with said preheating tube, whereby the liquid fuel is gasified in its passage through said tube.

CHARLES H. SWANSON.
